UNITED STATES PATENT OFFICE.

WILLIAM A. MALONEY, OF NEWTON, MASSACHUSETTS.

DETACHABLE RUBBER HEEL.

Application filed June 15, 1921. Serial No. 477,812.

To all whom it may concern:

Be it known that I, WILLIAM A. MALONEY, a citizen of the United States, residing at Newton, in the county of Middlesex and State of Massachusetts, have invented a new and useful Detachable Rubber Heel, of which the following is a specification.

This invention relates to a detachable rubber heel and particularly to improved devices for attaching the heel to a shoe. It is the general object of my invention to provide attaching devices of simple construction, so designed that they may be economical in manufacture, reliable in service and easily attached or detached as desired.

My invention further relates to arrangements and combinations of parts which will be hereinafter described and more particularly pointed out in the appended claims.

20 A preferred form of my invention is shown in the drawings in which—

Fig. 1 is a partial side elevation of a shoe showing my detachable heel construction in sectional elevation, taken on the line 1—1 in Fig. 2;

Fig. 2 is a plan view of the detachable heel;

Fig. 3 is a bottom view of the heel lift to which the detachable heel is secured;

30 Fig. 4 is a sectional elevation of separated portions of the heel and lift, including one of the attaching devices;

Fig. 5 is a view similar to Fig. 4 but showing the parts assembled;

35 Fig. 6 is a plan view of one of the toothed plates which are fixed in the heel; and

Fig. 7 is a perspective view of one of the washers which are embedded in the heel lift.

Referring to the drawings, I have shown 40 a portion of a shoe 10 having a heel lift 11 secured thereto in any usual or desired manner. The lift 11 is provided with a plurality of recesses 12, certain of these recesses being surrounded by washers 13 embedded in the 45 material of the heel lift which is preferably made of hard rubber.

The heel 14 is provided with a plurality of integral projections 15 located to correspond with the recesses 12 in the heel lift. 50 Metal plates 16 are molded in the body of the heel, these plates being associated with certain of the projections 15 and having upwardly extending toothed portions 17 each 55 preferably embedded or partially surrounded by its associated projection. Slots 18 (Fig. 3) may be provided at the edges of

the recesses 12 to permit the entrance of the projection 17 therein.

The heel is secured to the heel lift by simply inserting the projections 15 in the 60 recesses 12 and forcing the parts together until the teeth of the portions 17 engage the inner edges of the corresponding washers 13, as clearly shown in Fig. 5. The parts are thus firmly held together at a number 65 of separated points and the heel cannot be accidentally displaced.

I provide, however, for the removal of the heel by forming two openings 19 in the breast of the heel lift 11, these openings 70 extending into the inner ends of two of the recesses 12 and permitting the insertion of rods 20 (Fig. 5) to force the corresponding toothed portions 17 rearward and thus disengage the teeth from the washers 13. 75 When the front edge of the heel is thus freed, the entire heel may be removed by bending the heel downward from the front edge. The resilience of the projections 15 80 yieldingly holds the toothed portions 17 in engagement with the washers 13 but permits the portions 17 to be forced backward to release the heel.

It will thus appear that I have provided an extremely simple and reliable construction by which a heel may be detachably secured to a shoe without the use of any separately movable parts. It will be further evident that changes and modifications can be made in my invention by those skilled in 90 the art within the spirit and scope thereof as set forth in the claims and I do not wish to be otherwise limited to the details herein disclosed but what I claim is:—

1. In a shoe, a heel lift and a rubber 95 heel detachably secured thereto, said lift having a plurality of recesses bordered by rigid members and said heel having integral projections corresponding in size and position to said recesses and having upwardly 100 extending toothed plates associated with said projections and effective to engage said rigid members and to secure the heel in position each projection cooperating with its associated plate to hold the same in locking engagement with one of said rigid members. 105

2. In a shoe, a heel lift and a rubber heel detachably secured thereto, said lift having a plurality of recesses bordered by rigid members and said heel having integral projections corresponding in position to said recesses and having also a plurality of plates 110

embedded therein with toothed portions thereof extending upward and partly enclosed by said projections, said toothed portions engaging said members to prevent separation of the heel and lift and said parts being assembled by a direct movement of approach with the parts in normal and substantially flat position.

3. In a shoe, a heel lift and a rubber heel 10 detachably secured thereto, said lift having a plurality of recesses bordered by rigid members and said heel having toothed plates embedded therein and extending upwardly therefrom, said plates engaging said members when the parts are yieldingly assembled 15 by a direct movement of approach and preventing separation thereof, and said lift having openings communicating with cer-

tain of said recesses to facilitate separation of said plates and members.

4. In a shoe, a heel lift and a rubber heel 20 detachably secured thereto, said lift having a plurality of recesses bordered by metal washers embedded in said lift and spaced from the face thereof and said heel having a 25 plurality of plates fixed therein with toothed projections extending upwardly at right angles to said heel and plates and engaging the inner edges of said washers to secure the heel in position, said parts being yieldingly 30 assembled by a direct movement of approach and being positively held from separation.

In testimony whereof, I have hereunto affixed my signature.

WILLIAM A. MALONEY.
